UNITED STATES PATENT OFFICE.

JAMES F. MAYS, OF BIRMINGHAM, ALABAMA, ASSIGNOR TO MAYS ACCOUNTING MACHINE COMPANY, OF LEXINGTON, NORTH CAROLINA, A CORPORATION OF NORTH CAROLINA.

QUOTIENT-REGISTERING MECHANISM FOR CALCULATING-MACHINES.

1,297,711.

Specification of Letters Patent.

Patented Mar. 18, 1919.

Application filed April 30, 1917. Serial No. 165,413.

To all whom it may concern:

Be it known that I, JAMES F. MAYS, a citizen of the United States, residing at Birmingham, in the county of Jefferson and State of Alabama, have invented certain new and useful Improvements in Quotient-Registering Mechanism for Calculating-Machines, of which the following is a specification.

10 This invention relates to improvements in quotient registering mechanism in which the quotient is automatically registered on a series of dials, and in the case shown by the operation of the ordinary finger keys of the machine, though I do not limit my invention to calculating machines in which the setting of the dials is limited to direct key operation.

The invention further relates to improvements in quotient registering mechanisms in a calculating machine having a series of movable division indicators or decimal pointers, and wherein there is provided mechanism common to both the decimal pointers and the quotient registering mechanism, and so arranged that when manipulated will operate the desired decimal pointer, and at the same time select the proper quotient registering dial to be registered upon. It is old in calculating machines to point off decimal places in a number registered on a series of dials, by manipulating movable decimal pointers mounted on the top of the machine casing, and to employ quotient registering dials for registering the quotient, but in all such machines there has not been any operative connection between the decimal pointers themselves and the quotient dials. The disadvantage of such arrangements is that the setting of the decimal pointers and the selective setting of the quotient registering dials involves two separate and independent operations, and a person is liable to perform one and forget to perform the other, and even if they perform both, they may not be performed in the proper relation to each other. In other words, this arrangement involves a human element which is largely susceptible to error.

45 In my improved device the selective operation of the quotient registering dials and the decimal pointers are so connected as to eliminate this liability of human error.

Further objects of my invention will ap-

pear from the following description, and 55 the novel points will be more particularly pointed out in the accompanying claims.

In order to more fully describe my said invention, reference will be had to the accompanying drawings wherein:

Figure 1, represents in top plan a calculating machine embodying my invention;

Fig. 2, a fragmentary view of the machine with the casing removed, and showing parts of my invention in rear elevation;

Fig. 3, a side elevation partly in section of parts of the mechanism constituting my invention;

Fig. 4, a fragmentary top plan view partly in section of the same;

Fig. 5, a detail section on line 5^x—5^x Fig. 4, looking in the direction of the arrows, and

Fig. 6, a detail section on line 6^x—6^x Fig. 4, looking in the direction of the arrows.

It will be assumed for the purpose of the present description that my invention is applied to that general type of calculating machine in which the ordinary addition dials are operated from rock shafts actuated by the keys such, for example, as shown in my United States Patents Nos. 838,128 and 1,220,665. However, the invention can be used on other types of calculating machines.

In the accompanying drawings, 1 represents the casing of such machine, 2 the keys, and 3 the number dials operated from these keys for purposes of performing the operations of addition, subtraction, multiplication and division, the said dials in the machine shown being provided with two sets 90 of numbers, the upper set reading on each dial from 0 to 9, and the lower set being numbers which are complementary to the numbers of the upper set. The dials are displayed through windows 4 and 5, respectively, formed in the casing 1. Hand operated lever 6, shown in Fig. 1, is for the purpose of resetting the dials 3, and forms no part of my present invention.

The improved division counter or quotient 100 registering mechanism constituting my present invention comprises in the form shown, among other parts, a series of registering dials 7^a, 7^b, 7^c, 7^d, 7^e and 7^f, each mounted to turn on an individual shaft 8, mounted in side frames 9 and 10 secured to the general frame of the calculating machine, and located directly inside of the right-hand side

thereof so as to be inclosed in the casing 1. These dials, however, may be placed at either right or left side of the machine keys, as desired. Some calculating machines are better 5 adapted for using them on the left side. These dials 7^a—7^t are each provided with numbers reading from 0 to 9 inclusive, which are adapted to be displayed through window openings 11, formed in casing 1. 10 Each of these dials is under tension of a coil spring 12 tending to rotate it in an anti-clockwise direction Fig. 3, but normally held in its zero position against such rotation, by a pin 8' on each shaft 8 engaging with a 15 stationary pin 9' on frame 9. Each dial 7^a—7^t is provided with a holding pawl 13 adapted to engage with the teeth of a ratchet 14 fast to each of said dial shafts, the said holding pawls being under tension in a direction toward said ratchets, of a spring 15. For the purpose of stepping these dials 7^a—7^t forward, there is provided a master ratchet shaft 16 slidably mounted at one end 20 in a sleeve 17 and slidably mounted at its other end in a rigid bar 18 forming a portion of the framework of the machine. This shaft is also rotatable in parts 17 and 18. Horizontal movement is imparted to shaft 16 for the purpose of operating dials 7^a—7^t, 25 and rotary motion is imparted thereto for the purpose of selecting which of said dials shall be operated. This shaft operates said dials through a series of pawls 19 fast to said shaft, which are adapted to engage respectively with ratchets 14 fast to the respective dial shafts 8. Shaft 16 is seven-sided in cross-section, and pawls 19 are spaced spirally around the same so that in one angular position of the shaft one of said 30 pawls will be operative upon dial 7^a, for example, and when said shaft is rotated one-seventh of a revolution, that pawl will be shifted out of operative relation to said dial, and the next pawl brought into operation to 35 dial 7^b, and so on through the series. Longitudinal movement is imparted to shaft 16 to step the dials 7^a—7^t forward through the operation of the keys 2 of the machine, and this is effected by means of the following 40 mechanism: Shaft 16 carries near one end and fast thereto a flanged collar 20, which engages with a pin 21 carried by an arm 22 of a bell crank lever 23. The other arm of this lever is flexibly connected through a 45 link 24 to a lever or arm 25 fast on a rocker shaft 26 which carries fast thereto an arm 27, said rock shaft being journaled at one end in angle plate 28 and at the other, in frame piece 29 of the machine. Arm 27 normally stands in engagement with one of a 50 series of pins 30 fast on a movable bar 31 pivotally mounted on rocker arms 32 and 33 having movable guides 32' and 33' adapted to coöperate with rigid guide plates 34 and 55 35. Shaft 16 is constantly under tension to

the right of a spring 36 which also acts to hold arm 27 against pin 30. Bar 31 is at all times under tension to the right, Fig. 2, of a spring 37. Each time one of the keys of the machine is operated, bar 31 is shifted to the 70 left Fig. 2, and actuating through its connection with shaft 16 imparts horizontal movement to this shaft to the left as shown in Fig. 3, thereby stepping that one of said dials 7^a—7^t around one step, which happens 75 to be in operative relation with one of the pawls 19 on said shaft.

For the purpose of effecting the above described operation of bar 31 from the keys, there is provided the following mechanism: 80 Each pin 30 corresponds to a column of keys and corresponding to each such pin there is an arm 39 rigidly mounted on a rock shaft 40, and these arms are adapted, upon the operation of their respective rock shafts 85 through a portion of a revolution, to engage with their respective pins 30 and shift the latter, and, therethrough, the bar 31 to the left Fig. 2. For the purpose of imparting rotation to the rock shafts 40, the stem portion 38 of each key, in the case shown, is provided with a series of gear teeth 41 which, when the key has been depressed a given distance, engage with toothed sectors 42 of the individual rock shafts 40. Each of these 95 sectors is provided with an extension or arm 43 adapted to be engaged by a pin 44 on its respective key stem, and operated by said pin so as to impart a preliminary or initial angular movement to the sector, causing it 100 to readily engage with the gear teeth 41 on the key stems.

The rotation of shaft 16 for the purpose of selecting that one of the dials 7^a—7^t which is to be operated, is effected automatically through the setting of division indicators or decimal pointers 45, and for this purpose there is provided the following mechanism: The end of shaft 16 which extends into sleeve 17 is slotted, as at 16', 110 and into this slot extends a pin 17' so as to effect a positive connection between shaft 16 and sleeve 17 so far as rotary motion is concerned. Sleeve 17 is rotatably mounted near one end in a fixed plate 46, 115 and at its other end is provided with an extension 47 forming a stud shaft which is rotatably mounted in a fixed plate 48. Loose on extension 47 of sleeve 17 is a gear 49 which carries a spring pawl 50 adapted to 120 engage with a ratchet 51 formed on a gear 52 fast on or integral with sleeve 17. Gears 52 mesh with a gear 53 formed on a registering dial 54 fast on a shaft 55 journaled in plates 46 and 48. The function of this dial 125 will be later described. Gear 49 meshes with a gear 56 loose on shaft 55. Gear 56 is constantly under tension in an anti-clockwise direction, Fig. 5, of a coil spring 57 attached at one end to a pin 58 fast to one 130

face of said gear, and at its other end to a pin 59 on an arm 60 rigidly attached to the frame of the machine and acting against pin 58 to form a stop to limit the movement 5 of gear 56 in the direction above stated. Gear 56 also carries a pin 61 fast thereto, and adapted to engage with one end of a ratchet bar 62 slidably connected to the inside of the top casing of the machine for 10 horizontal movement, and constantly under tension to the left, Fig. 4, of a spring 63. Rigidly attached to the inside of said top casing is a supporting bar 64 upon which is slidably mounted, each upon a pair of 15 pins or screws 65, a series of plates 66 located alternately on opposite sides of said bar. Each of these plates is provided with an upward extension 67 (see Fig. 5) which passes through an individual slot 68 in the 20 top casing of the machine, and each of these plates is under tension of an individual spring 69 at all times tending to hold said upward extensions against corresponding ends of their individual slots 68, the left- 25 hand ends thereof as shown in Figs. 4 and 5. Each of the extensions 67 terminates at its upper ends in a finger-piece 70 for operation as hereinafter described. On each of the decimal pointers 45 is formed a pivot 30 pin 71 rotatable in the top casing of the machine, and each of these pins is provided with an arm 72 fast thereto and adapted to be engaged by the forward edge of a corresponding one of the plate extensions 67. 35 Also adapted to engage respectively with the forward edge of these extensions are a series of offsets or shoulders 73 formed on the ratchet bar 62. Therefore, if the fore-finger be pressed against the right-hand side 40 of one of the finger-pieces 70, Fig. 5, and the thumb against the left-hand side of the next finger-piece on the left, the latter will be shifted to the right against the tension of its spring 69, thereby causing the extension 67 acting through that one of the shoulders 73 in engagement therewith to shift ratchet bar 62 forward or to the right in Fig. 5 so as to rotate gear 56 one step. At 45 the same time extension 67 acting through arm 72 operates its corresponding decimal pointer 45, causing the same to travel in an anti-clockwise direction or point downward to a corresponding one of a series of division lines 74, appearing on the top of the 50 machine casing between successive dials, and indicating the decimal points. In imparting the rotation to gear 56 described, this gear acted through gear 49 and its ratchet connection with gear 52 to rotate sleeve 17 55 and therethrough shaft 16, to bring that one of its pawls 19 into operative relation with that one of the registering dials 7^a—7^t, corresponding to the decimal pointer operated. It will therefore be seen that mechanism is 60 provided whereby the operation of a given 65

decimal pointer automatically selects the quotient registering dial corresponding to the decimal pointer operated.

For the purpose of forming a check on the last quotient dials 7^a—7^t operated, in case the operator of the machine is called away or otherwise interrupted in the midst of a calculation, the registering dial 54 is provided for recording the number of the quotient dial being operated. This dial 54 carries upon its periphery numbers 0, 1, 2, 3, 4, 5 and 6, in the case shown, corresponding, excepting as to the zero, to the number of quotient registering dials employed, and is rotatable with shaft 55, geared to a gear 52 fast to sleeve 17 so that for each step that shaft 16 is rotated, a new number on dial 54 will be displayed through an opening 75 thereabove formed in the top casing of the machine. 85

For the purpose of resetting the quotient dials 7^a—7^t to zero, there is provided, in the case shown, a longitudinally shiftable bar 76 at all times under tension to the right Fig. 3 of a spring 77, and carrying a series 90 of pins 78 individual respectively and in line with the upward extension formed on dial pawls 13. This bar 76 is provided with an extension 79 which passes upwardly through a slot 80 in the top casing, and forms a handle for the lateral shifting of said bar. By shifting said bar to the left, Fig. 3, pins 78 thereon engage with pawls 13 and release the same from engagement with their respective ratchets 14, whereupon 100 the latter rotate backward under the action of their individual springs until pins 8' on the shaft of each of said ratchets engages with their stationary stop pins 9', whereupon 105 each of the quotient dials displays zero through its opening 11 in the top casing. 110

Mechanism may also be provided for coupling and uncoupling the division counting mechanism to and from operative connection with the keys, and this is effected in the present case by mounting the arms 32 and 33 which carry bar 31 upon a horizontally shiftable frame 81, guided by screws 82 passing through slots 83, and shifted by means of a lever 84 fulcrumed on a shaft 85, and having an extension 86 engaging at its lower end with a pin 87 secured to the shiftable frame 81. For effecting an even movement of frame 81, there is fast on shaft 85 an arm 88 engaging at its lower end with a pin 89 fast on frame 81. When the upper end of lever 84, which extends through a slot in the top casing of the machine, is shifted to the left Fig. 3, the pins 30, or bar 31, are brought out of the paths of arms 39, and 125 when shifted to the right Fig. 3, said pins are carried forward or into the paths of said arms, and therefore into operative relation thereto.

There is also preferably provided on the 130

top casing of the machine a series of lines 90 leading from the spaces between adjacent columns of keys to the pivotal points of the corresponding decimal pointers.

5 The operation is as follows:

Assume, for example, that it is desired to divide 8575 by 35. The operator first sees that all of the dials 7^a—7^c stand at zero, and that the dial 54 also indicates zero, and he 10 then sets the number 8575 on the complementary numbers of the dials 3, as indicated in Fig. 1, and he manipulates that one of the finger-pieces 70 which will operate the proper decimal pointer 45 to point off 15 85; that is, the second decimal pointed from the right Fig. 1. The operator then operates the 3 key in the fourth column from the right, and the 5 key in the third column from the right, depressing these keys simultaneously, and repeats this operation until 20 the dividend 85 is reduced to less than 35. 35 will go into 85 twice; therefore the first quotient registering dial 7^a will display the numeral 2. The registering dials 3 which 25 formerly displayed the dividend 85 will now display 15. The operator then turns down the next decimal pointer on the right, which points off a dividend 157. The operator then operates the 3 key in the third column, and 30 the 5 key in the second column until the dividend 157 becomes less than 35. 35 will go into 157 at least four times, and the second quotient registering dial 7^b will now display the numeral 4. The remainder left in the 35 dividend will be 17 which will be displayed on the second and third dials 3 from the right, Fig. 1. The actual dividend to be now divided into is 175, which will be displayed by the last three dials 3 on the right, and being the last figure in the dividend, it 40 is not necessary to point off any decimal place. However, in order to select or render operative the next quotient registering dial (dial 7^c) one of the finger-pieces 70 is operated as hereinbefore described so as to rotate the selecting ratchet shaft 16. The operator then manipulates the 3 key of the second column from the right, and the five key of the last column on the right, until the 45 number displayed by the dials 3 is less than 35, whereupon the quotient registering dials 7^c will display the number 5. As 35 goes into 135 an even number of times, no remainder will be left on the dials 3. If there 50 were a remainder, this would show up on the dials 3.

Before commencing each operation of division, the dials 7^a to 7^c are all set to zero, and the auxiliary dial 54 is also set to display zero. When the first decimal pointer was turned down, the ratchet bar 62 stepped gear 56 forward one step, and this not only rotated shaft 16 so as to bring one of its pawls 19 into operative relation with dials

7^a, but it also stepped dial 54 around one step, causing this dial to display the numeral 1, indicating that the quotient dial being operated upon is the first one in the series. Similarly this dial 54 will be stepped around one step each time a new dial of the series 7^a to 7^c is employed in the operation, so that if an operator is interrupted or called away in the midst of an operation, he will know which one of the dials 7^a—7^c will operate on the next manipulation of the keys.

I have herein shown and described but one specific embodiment of my invention, but it is understood that the same may be modified in many respects without departing from the spirit of my invention.

What I claim is:—

1. In a calculating machine, the combination with a series of movable decimal pointers, a series of quotient registering dials, mechanism for selecting one of said dials at a time for operation, and mechanism automatically acting upon the movement of one of said decimal pointers to point off a decimal place and adapted to actuate said selecting mechanism to render operative that one of said dials corresponding to the decimal pointer operated.

2. A calculating machine comprising a movable decimal pointer, manually operated means for operating said decimal pointer, a series of quotient registering dials and means for operating the same, and mechanism also operated by said manual means to select a quotient dial corresponding to the decimal pointer operated.

3. A calculating machine comprising a movable decimal pointer, dial selecting mechanism, dial operating mechanism, and means common to both said decimal pointer and selecting mechanism for operating the same.

4. A calculating machine having a top casing provided with a series of slots, a series of finger operated members extending each through an individual one of said slots and mounted within said casing, means holding said members under tension against corresponding ends of said slots, a series of decimal pointers individually operable by said members, quotient registering dials and means to operate the same, and quotient dial selecting mechanism also operable by said members.

5. A calculating machine comprising a series of quotient registering dials, a rotary dial selecting member provided with means individual to the respective dials for operating the same one at a time, and mechanism operative on said member to rotate the same to effect said selection.

6. A calculating machine comprising a series of quotient registering dials, a rotary dial selecting member provided with means

individual to the respective dials for operating the same one at a time, and mechanism operative on said member to rotate the same always in the same direction to effect

5 said selection.

7. A calculating machine, comprising a series of quotient registering dials, a ratchet operatively connected to each of said dials, a shaft having a series of pawls arranged thereon in a spiral path, means to rotate said shaft to bring said pawls successively into operative relation to successive ones of said dial ratchets, and mechanism to shift said shaft longitudinally to operate said ratchets

10 by said pawls and therethrough to operate corresponding ones of said dials.

8. A calculating machine comprising a plurality of key operated rock shafts, a movable bar common to said shafts, means for shifting said bar through the rotation of any of said shafts, a series of quotient registering dials each having a ratchet operatively connected thereto, a rotatable and longitudinally shiftable shaft, operative 20 connection between said movable bar and said shaft for longitudinally shifting the same, a series of pawls mounted on said shaft in a spiral path and adapted to engage successively with corresponding ones 25 of said dial ratchets and means to rotate said shaft step-by-step.

9. A calculating machine comprising a series of quotient registering dials, means for actuating said dials individually, 30 division indicators corresponding to the quotient dials, and means operative by the respective division indicators for auto-

35 matically setting the corresponding quotient dials for actuation.

10. A calculating machine, comprising a series of quotient registering dials, means for rotating said dials individually, key operated means for operating said dial rotating means to rotate said dials, mechanism for bringing said dial operating means into 40 and out of operative relation to said dials, decimal pointers, decimal pointer operating means, and finger operated means common to both said mechanism and said pointer operating means to simultaneously operate 45 50 the same.

11. A calculating machine having a casing the top of which is provided with a series of slots, a series of finger operated members extending each through an individual one of said slots and mounted within said casing, means holding said members under tension against corresponding ends of said slots, quotient dials and means to operate 55 the same, and quotient dial selecting mechanism operable by said members.

12. A calculating machine comprising a series of quotient registering dials, means to select individual ones of said dials for operation, means to operate said dials selected, an auxiliary or dial indicating dial, and mechanism to impart rotary motion to said last named dial each time one of said quotient 60 65 dials is selected for operation.

In testimony whereof I affix my signature 70
in the presence of a witness.

JAMES F. MAYS.
